United States Patent Office.

JAMES TEACHOUT, OF WATERFORD, NEW YORK.

Letters Patent No. 72,116, dated December 10, 1867.

IMPROVEMENT IN KNITTING-MACHINES.

The Schedule referred to in these Letters Patent and making part of the same.

TO ALL WHOM IT MAY CONCERN:

Be it known that I, JAMES TEACHOUT, of Waterford, in the county of Saratoga, and in the State of New York, have invented a new and useful Improvement in "Jacks" or Loop-Lifters to Knitting-Machines; and I do hereby declare that the following is a full, clear, and exact description of the construction and operation of the same, reference being had to the annexed drawing, making a part of this specification, in which—

Figure 1 is a top view, and

Figure 2 is a vertical central section of the jack-holding device, showing the manner in which the jacks or loop-lifters are jointed or hinged at their extremity; and

Figure 3 is a side, and

Figure 4 an edge or top view of my elongated jack or lifter.

The object of this invention is to dispense with the use of wheel "burrs" heretofore used within needle-cylinders, by so forming "jacks" or lifters as to obviate the difficulty arising from the use of E. M. Ray's patent jacks, to wit, when the jacks are lifted sufficiently high to cast off the loop or stitch beyond the end of the needle, the said jacks will as often return down on the opposite side of the needle, on account of its necessary narrowness at that point of the jack. My improvement also obviates the bending and breaking of needles, by giving said needles the required lateral support, as will be hereinafter explained.

A, figs. 1 and 2, is the jack-retaining device, applied to the centre of the needle-cylinder, and so formed as to retain loosely the inner ends of the jacks or lifters B, in such a manner that they may be elevated or depressed the required radii; and in order to effect this, a circular groove, c, is turned or formed in the hub A and cap or plate D, as is shown, and the rounded ends of the jacks are retained therein, as is represented in figs. 1 and 2. The jacks are made of thin steel, tempered, &c. E, figs 2 and 3, shows the way in which the needles are supported in a lateral way, by a projecting arc, f. An arch, g, is formed on the upper edge of the jacks for the purpose of depressing the "cloth" below a level with the base of the needles, or where they are leaded, as is the case with wheel "burrs."

This invention is an improvement on the patent granted to E. M. Ray, May 30, 1854, and overcomes, in my opinion, all the objections found to exist in his apparatus.

Extremely fine hose of small calibre can be manufactured on my invention, by dispensing with the use of the "inside" burrs.

Having thus described my invention, what I desire to secure by Letters Patent, is—

1. Forming the "jacks" or loop-lifters B, with a projecting arc, f, and depressed arch g, for the purposes set forth.
2. In combination with the arc f and arch g, I claim the rounded end, as shown and described.
3. I claim, in combination, with the described knitting-jacks, a retaining-hub or device, constructed and arranged as shown and described.

JAMES TEACHOUT.
